ASH TRAY

William F. Vernon, Newton, Iowa, assignor to
The Vernon Company, Newton, Iowa

Filed Jan. 5, 1962, Ser. No. 68,199

Term of patent 14 years

(Cl. D85—2)

FIG. 1

FIG. 2

FIG. 3

FIG. 4

FIG. 5

FIG. 6

FIGURE 1 is a top plan view of an ash tray, showing my new design;

FIGURE 2 is a bottom plan view;

FIGURE 3 is a side elevational view;

FIGURE 4 is a front elevational view; and

FIGURE 5 is a rear elevational view; and
FIGURE 6 is a sectional view taken through the vertical diameter of FIG. 1.

I claim:

The ornamental design for an ash tray, as shown.
